(57) **CLAIM**

The ornamental design for a patch tag, as shown and described.

DESCRIPTION

FIG. 1 is a front perspective view of a first embodiment of a patch tag, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front perspective view of the second embodiment of the patch tag;

FIG. 9 is a front perspective view of FIG. 1 shown in an environment of use;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a top plan view thereof;

FIG. 15 is a bottom plan view thereof;

FIG. 16 is a front elevation view shown in an alternate environment of use; and,

FIG. 17 is a front elevation view of the third embodiment of the patch tag, the back elevation view being a mirror image thereof.

The broken lines show portions of the article that do not form part of the claimed design.

the broken lines showing patches on front and rear surfaces in FIGS. 9-16 show environment that form no part of the claimed design.

1 Claim, 17 Drawing Sheets
